ABRADING IMPLEMENT

Albert Field, Dayton, Ohio

Application December 13, 1954, Serial No. 474,669

2 Claims. (Cl. 51—195)

This invention relates to abrading implements and particularly to abrasive coated flexible sanding and like discs which are mounted on a mandrel for application to the work, the mandrel in turn being installed in a rotary hand-held power tool or the like.

It has heretofore been proposed to embody in such discs a hollow internally threaded metal grommet having the dual function of holding the several plies of the sanding disc in assembled relation, in the case of a multiply disc, and also of enabling a positive driving engagement of the disc with the mandrel without the use of bolts and separable nuts, the mandrel having a threaded tip which is received in the interior of the grommet. The disc is composed essentially of a fabric material and while it fits relatively closely upon the grommet it has been possible for the ferrule to turn relatively to the disc, particularly under high speed operation and upon the imposition of relatively high resistance to rotation of the disc.

It is the object of the invention to obviate slipping of the disc and grommet relatively to one another, and it is an attendant object in this connection to prevent such slipping without the use of accessory devices which would add to the complication and cost of the disc assembly.

In the drawing,

Fig. 1 is a view in side elevation of a disc and mandrel assembly, showing the disc mounted on the mandrel;

Fig. 2 is a view in front elevation of a sanding disc in accordance with the illustrated embodiment of the invention;

Fig. 3 is a detail fragmentary view of the disc of Fig. 2 in longitudinal section; and

Fig. 4 is a detail fragmentary view taken substantially along the line 4—4 of Fig. 3.

Referring to the drawings, an abrading implement in accordance with the instant illustrated embodiment of the invention comprises a disc 10 made up of multiple superposed plies of a fabric material coated with an abrasive, and the several plies may be cemented together to define a unitary disc construction. A plurality of cuts 11 and 12 may be formed in some or all of the plies of the disc for greater flexibility in the peripheral area. The disc has a central through opening 13.

Installed in the opening 13 is a grommet 14 having a cylindrical portion 15 in contact with the wall of the opening 13, and further having at one end thereof a flange 16 lying outside the opening 13 and turned over upon the body of the disc 10. At its opposite end the grommet extends outside the opening 13 and terminates

2

in a relatively large annular head portion 17. The disc 10 is clamped between the end portions 16 and 17 of the grommet by upsetting the end 16 substantially to the position shown.

5 The interior of the grommet 14 is threaded in a manner to receive a threaded tip 18 on a mandrel 19. The tip 18 projects from a relatively large diameter shoulder 21 at the base of the mandrel 19, which shoulder abuts the end portion 16 of the grommet, and the surface of the disc, in a way to complement or to oppose the large head portion 17 of the grommet. The mandrel 19, as may be seen in Fig. 1, further includes a shank portion 22 for reception in the chuck of a power tool.

The enlarged head portion 17 has a circumferential series of cut out portions 23 in its periphery, each such portion being substantially crescent-like in shape and defining sharp edges 24. Under compressive influences applied in installing the grommet 17, and in response to relative rotation between the disc and grommet, the edges 24 tend to imbed themselves into the fabric of the disc. The disc and grommet are thereby in effect locked together for unison rotation. It will be understood that the disc 10 is rotated by virtue of its mounting on the mandrel 19, the mandrel rotating relatively to the disc until the tip 18 penetrates fully into the grommet 17 and until the shoulder 21 seats on the end 16 of the grommet and on the disc. When this occurs, continued rotary motion of the mandrel is partaken of by the grommet, and, by virtue of the gripping connection above described, by the disc 10 as well. It will further be noted that the edges 24 are arranged to imbed themselves in the fabric of the disc in either direction of rotation so that should the direction of rotation of the mandrel be reversed, as to withdraw the mandrel from the grommet, the ferrule will be precluded from following the motion of the mandrel relatively to the disc.

What is claimed is:

1. An abrading implement, including a multiply disc made up of an abrasive coated fabric material, an internally threaded grommet installed in said disc holding said plies in superposed contacting relation, one end of said grommet having a planar surface in approximately parallel contacting relation to the exposed surface of a terminal one of the superposed plies and the interior of said grommet being open to receive the threaded end of a mandrel whereby to support and to rotate said disc, and cut-outs in the periphery of said one end of the grommet opening through said planar surface to define therewith sharp edges tending to imbed themselves in the fabric of said one ply in response to relative rotation of said grommet and disc.

2. An abrading implement according to claim 1, characterized in that said cut-outs are approximately crescent-like in shape, the walls of which are inclined outwardly from the opposite end of the grommet to the said one end thereof to define with said planar surface the said sharp edges.
